UNDERCUTTING BUCKET

Matt R. Peck, Gardena, Calif., assignor of one-half to Benjamin E. Bertran and one-half to Josie A. Bertran, both of Los Angeles, Calif.

Application August 1, 1936, Serial No. 93,819

9 Claims. (Cl. 255—74)

This invention relates to excavating tools, and particularly pertains to an under cutting bucket.

In various excavation operations, and particularly when concrete footings are to be set in the ground it is necessary to excavate a bore to receive a column of concrete, and it is desirable to enlarge the size of the excavation at the lower end of the bore to provide an enlarged footing for the concrete column. The bore is usually made with some suitable type of drilling tool and the enlarged cavity at its lower end may be made by the use of under cutting tools or under reamers. These structures often are difficult to handle and manipulate within the bore, and do not always insure that the earth which is cut away to form the enlarged base of the bore may be conveniently removed. It is the principal object of the present invention to provide a boring tool embodying an under cutting bucket in its construction whereby a straight bore hole of uniform diameter may be made and an enlarged space created at the bottom of the bore or at any point along its length as controlled and manipulated by the operator at the top of the bore. The structure also embodies simple means for catching the cuttings and permitting the cuttings to be removed from the bottom of the bore hole.

The present invention contemplates the provision of a guide cylinder adapted to extend into a bore hole as carried by a drill stem. Secured to the lower end of the guide cylinder is an under cutting bucket which is articulately connected thereto for lateral swinging movement, and which may be disposed at a desired angle to the vertical and thus held while an under cutting operation is carried out, the bucket carrying blades by which the earth may be cut and the cuttings being diverted into the bucket.

The invention is illustrated by way of example in the accompanying drawing in which:

Figure 1 is a view in vertical section and elevation with parts broken away and showing the application of the present invention to a well bore.

Fig. 2 is a view in vertical section through the under cutting bucket as seen on the line 2—2 of Fig. 1.

Fig. 3 is a view in elevation showing the structure with which the present invention is concerned as viewed in the direction of the arrow 3 in Fig. 1.

Fig. 4 is a view in transverse section through the under cutting bucket as seen on the line 4—4 of Fig. 1.

Referring more particularly to the drawing 10 indicates a Kelly bar which is preferably square in cross section at the lower end of which is a drill string coupling 11 by which a drill string or a drill bar 12 is attached to the Kelly bar. The bar 10 extends through a conforming square hole

in a rotary table 13 and is therefore driven thereby while having vertical movement with relation thereto. The rotary table may be of any desired design and is here shown as fitted with a gear 14 engaged by a pinion 15 and driven from a suitable source of supply through a shaft 16. Suspended from the rotary table is a guide cylinder 17 which is supported by an operating rod 18. The upper end of this rod is fitted with a nut 19 holding it with relation to the table, and at its lower end with a nut or head 20 which extends through the upper end plate 21 of the guide cylinder 17. The lower end of the guide cylinder 17 is fitted with an end spider 22 having a central hub 23 therethrough and through which the drill stem 12 extends. The terminating end of the drill stem 12 is provided with a transverse pin 24 carrying rollers 25, one of which is positioned on each side of the drill stem 12, as particularly shown in Fig. 2 of the drawing. The rollers extend into grooves 26 between trackways 27 and 28. These trackways are mounted across the upper end of the under cutting bucket 29. The under cutting bucket is substantially cylindrical and is hinged to the spider 22 of the guide cylinder 17 by suitable hinge 30 mounted at one edge of the cylinder. By reference to Fig. 1 of the drawing it will be seen that the lower end of the bucket is disposed obliquely to its central longitudinal axis so that the outer swinging portion of the wall of the bucket is longer than the inner edge and so that a pointed nose 31 will be formed. The bottom of the bucket is closed by two members, one being a bottom plate 32 and the other being a blade 33. The blade is disposed at an angle to the plane of the bottom plate, as particularly shown in Fig. 2 of the drawing, so that a throat 34 will occur between the central edges of the blade and the plate to accommodate the cuttings created by the advance 40 of the cutting edge 35 of the blade. It will be understood that the cutting edge 35 occurs on the center line of the bucket and that a longitudinally extending slot 36 is formed through the side wall of the bucket, one edge of the slot being 45 fitted with a side cutting blade 37. This blade occurs on the long side of the bucket 29 so that it will assume a downwardly and outwardly extending position to undercut the side wall of the bore 38 and form an outwardly flaring wall 39 to 50 create a space 40 for the footing which is to be made. At the same time it will be seen that the cutting edge 35 of the blade 33 will assume a substantially horizontal position to cut a flat floor 41 at the bottom of the bore. The floor plate 32 55 is hinged at 42 to the cylindrical wall of the bucket 29 and is temporarily held in its hinged position by a fastening 43.

In operation of the present invention the structure is assembled substantially as shown in Fig. 1 60

of the drawing. When the bore 38 of the excavation has reached a desired depth the device may be lowered into the bore with the rod 18 supporting the bucket, as indicated in dotted lines in Fig. 1. The drill rod 12 may then be rotated by the gear 14 carrying with it the Kelly bar 10 and drill bar 12 which revolves the guide 17 and bucket 29, the weight of the Kelly bar and drill rod tending to force the bucket outwardly on an incline, and as this is accomplished the handle 44 of the rod 18 is held so that as the drill stem 12 is forced downwardly it will act through the rollers 25 and guides 27 to force the lower end of the bucket 29 outwardly as it swings on its hinge 30. As the cutting operation proceeds the blade 37 will cut the inclined face 39 and the blade 35 will cut the horizontal face 41 of the footing space 40. It will be seen that as this operation proceeds the cuttings will be forced into the bucket 29 and may thereafter be removed as the bucket is withdrawn from the bore. Attention is also directed to the fact that the cylindrical guide sleeve 17 bears such a relation to the diameter of the bore 38 as to stabilize the bucket in its operation and to make it possible to move and swing the under cutting bucket outwardly and to hold it so that its cutting blade 37 will be maintained in cutting relation.

Attention is also directed to the fact that further cutting of a cylindrical hole may be performed after the original hole has been undercut.

It will thus be seen that the structure here disclosed is simple in construction and may be readily operated to undercut a bore in an excavation by the same rotary driving operation mechanism as is used to form the main bore.

While I have shown the preferred form of my invention as now known to me, it will be understood that various changes might be made in the combination, construction, and arrangement of parts by those skilled in the art without departing from the spirit of the invention as claimed.

Having thus described my invention, what I claim and desire to secure by Letters Patent is:

1. A digging tool comprising driving means, a dirt receiving member carried thereby and adapted to swing from a position vertically aligned with the rotary axis of the digging tool to a position downwardly and outwardly flaring with relation thereto, a blade on the side of said dirt receiving member adapted to cut an inclined face on the side wall of the bore within which the digging tool is operating and to deliver the cuttings into the receiving member and means operative from the top of the well to swing and maintain the dirt receiving member in cutting and noncutting positions.

2. A digging tool comprising guide means adapted to extend longitudinally within the bore of an excavation, means for rotating the same, an under cutting bucket hinged to the lower end of the guide means, means for swinging the under cutting bucket from longitudinally aligned positions to angularly disposed positions, and cutting blades on said bucket to cut walls of the excavation and to direct the cuttings into the bucket.

3. A digging tool comprising guide means adapted to extend longitudinally within the bore of an excavation, means for rotating the same, an under cutting bucket hinged to the lower end of the guide means, means for swinging the under cutting bucket from longitudinally aligned positions to angularly disposed positions, cutting blades on said bucket to cut walls of the excavation

and to direct the cuttings into the bucket, and means for releasing the cuttings from the bucket.

4. A boring tool comprising guide means to extend within the bore of an excavation, means for rotating the same, and a bucket carried at the lower end of said guide, said bucket being formed with side and bottom blades adapted to cut material from the bore and deliver it into the bucket, articulate means connecting the bucket to the guide means, and means operable from the top of the well for swinging the bucket laterally of the longitudinal axis of the guide and the bore to thereby selectively undercut the bore.

5. A boring tool comprising a guide cylinder 15 adapted to extend for a distance within a bored hole, means supporting the cylinder from the top of the hole and by which it may be raised, lowered, and rotated, a drill stem extending downwardly and reciprocating through said cylinder, an under cutting bucket pivoted to the lower end of said cylinder and operatively connected with the drill stem whereby relative movement of the drill stem with relation to the guide cylinder will cause the under cutting bucket to 20 swing toward and away from positions of vertical alignment with the cylinder, said bucket being formed with openings in its wall, and cutting blades disposed along one edge of said openings whereby rotation of the drill string, the guide 25 sleeve, and the bucket will cause the cutting blades to undercut the excavation bore and deposit the cuttings within the bucket to be removed therewith.

6. A digging tool comprising in combination 30 with a rotary driving table, a drill stem operatively associated therewith and extending downwardly into a well bore, a guide cylinder slidably mounted upon the drill stem, means supporting the guide cylinder from the rotary table whereby the 35 position of the cylinder with relation to the drill stem may be vertically adjusted, an under cutting bucket substantially cylindrical in section and normally disposed with its central axis in longitudinal alignment with the central axis of 40 the guide cylinder and hinged to one edge thereof, means operatively connecting said bucket with the drill string whereby relative longitudinal movement of the guide sleeve and the drill string will produce swinging movement of the under cutting 45 bucket, and cutting blades carried by the under cutting bucket for cutting an under cut wall at the bottom of the bore.

7. A boring tool including guide means to extend within the bore of an excavation, means for 50 rotating the same, and a bucket pivoted at the lower end of said guide at one side thereof, said bucket provided with cutting blades.

8. A boring tool including guide means to extend within the bore of an excavation, means for 55 rotating the same, means for supporting the same in the excavation, and a bucket pivoted at the lower end of said guide at one side thereof whereby it will swing laterally with the longitudinal axis of the guide and the bore, said bucket provided with cutting blades.

9. A boring tool including guide means to extend within the bore of an excavation, means for 60 rotating the same, means for supporting the same in the excavation, a bucket pivoted at the lower end of said guide at one side thereof whereby it will swing laterally with the longitudinal axis of the guide and the bore, and cutter means extending 65 from the walls of said bucket.
